UNITED STATES PATENT OFFICE

JOSEPH TAGLER, OF LOS ANGELES, CALIFORNIA

SHOE ATTACHMENT

Application filed April 29, 1929. Serial No. 359,012.

This invention relates to an improved athletic appliance in the form of an attachment for shoes, adapted to be worn by golfers, runners and analogous athletes, and it has 5 more particular reference to an accessory in the form of an anti-skid device, to be attached to the sole of the shoe to facilitate traction.

More explicitly stated, the invention has reference to an anti-skid appliance comprising a frame constructed to be attached to the bottom of a shoe sole, wherein the same is of an automatically adjustable self-conforming structure equipped with dependable retaining means and equally dependable anti-slipping carks.

In carrying the invention into effect, I have evolved and produced an unusually simple and inexpensive structure which is susceptible of easy and ready application and 20 removal, and capable of fulfilling the requirements of a device of this class in a satisfactory manner.

In the drawings:

Figure 1 is a bottom plan view of the attachment showing the approximate position 25 on a shoe sole.

Figure 2 is a side or edge elevation of Figure 1.

Figure 3 is a transverse section on the line 30 3—3 of Figure 1.

Figure 4 is a perspective view of the details.

Figure 5 is a perspective view of a complementary detail.

35 In carrying the invention into effect, I provide a flexible metal frame 6 of the configuration plainly seen in Figure 1. It is of general V-shaped outline, includes a web portion 7, and a pair of forwardly and outwardly diverging flat arms 8, and these are joined at their outer ends by a connecting strap 9, the end 10 of which is extended and bent upon itself to provide a sole engaging clamp 11. This clamp is of hook shaped design and is 40 adapted to take over the sole of the shoe as indicated in Figure 2. This frame is provided with a plurality of suitably shaped anti-slipping carks 12. Directing attention to Figure 3, it will be seen that the clamp 11 45 constitutes the stationary clamp and coop-

erates with the relatively adjustable or movable clamp 13.

This includes the hooked sole engaging clamp 14, and a flat body portion 15, having clips 16, slidably engaging the strap 9. The body portion 15 is provided with longitudinally spaced adjusting holes 17, and an especially designed cark 18 cooperates therewith. This cark comprises a retaining screw 19 and a cap like ground engaging element 20. It has the double function of providing an anti-slipping cark, and means for adjustably connecting the clamp 13 with the main frame.

The web portion 7 is provided with a longitudinal slot 21 through which the stem 22 of a retaining bolt is passed. This retaining bolt is of general T-shaped design and the cross head 23 is adapted to extend across the slot as indicated in Figure 1 to retain the frame in place. However, by turning the bolt one-quarter turn, the head 23 may be arranged in alignment with the slot 20 to permit the removal of the clamp. Cooperable with the slot is a connection element 24 carried by one end of a coiled spring 25. The opposite end of the spring is provided with an eye 26, which is engageable with an eye bolt 27 fastened to the arched portion of the shoe.

It will thus be seen that means is provided to retain the attachment in place on the shoe in a dependable manner and at the same time permit the desired degree of flexibility to facilitate comfortable as well as efficiently dependable results.

The simplicity is such as to make it unnecessary to enter into a more detailed description.

It is understood, however, that minor changes in the shape, size and materials coming within the field of invention claimed may be resorted to, in actual practice, if desired.

I claim:

1. In an attachment of the class described, a substantially V-shaped frame including a web portion and a pair of outwardly diverging arm portions, said arm portions being provided at their outer ends with relatively stationary and adjustable sole engaging jaws, said web portion being provided with a lon-

gitudinal slot, anti-slipping calks carried by said frame, a retaining bolt passing through said slot and adapted to be anchored in the sole of the shoe, a coiled spring connected at one end with said slot, and means for attaching the other end of the spring to the shoe sole.

2. As a new product of manufacture, an antislipping attachment for athletic foot wear comprising a substantially V-shaped frame including a slotted web portion and a pair of outwardly diverging arm portions, a connecting strap connecting the outer ends of said arms together and extending at one end and terminating in a hooked stationary sole gripping jaw, a slideable jaw adjustably mounted on said strap and cooperable with said stationary jaw, a substantially T-shaped retaining bolt having its stem portion passing through the slot and having its head portion associated with the slot in a manner to facilitate maintenance and also to facilitate removal of the frame, a spring connected at one end with the slotted web portion, and retaining means for the opposite end of the spring.

In testimony whereof I affix my signature.
JOSEPH TAGLER.
